UNITED STATES PATENT OFFICE

115,000

DESIGN FOR A RADIATOR ORNAMENT OR SIMILAR ARTICLE

Ludwig Maxenberger, East Cleveland, Ohio

Application February 23, 1939, Serial No. 83,149

Term of patent 7 years

To whom it may concern:

Be it known that I, Ludwig Maxenberger, a citizen of the United States of America, residing at East Cleveland, in the county of Cuyahoga and the State of Ohio, have invented a new, original, and ornamental Design for a Radiator Ornament or Similar Article, of which the following is a specification, reference being had to the accompanying drawing, forming part thereof.

In the drawing, Fig. 1 is a front elevation of the radiator ornament; Fig. 2 is a transverse central section as indicated by the line 2—2 on Fig. 1.

I claim:

The ornamental design for a radiator ornament or similar article, substantially as shown.

LUDWIG MAXENBERGER.
